Primary Examiner — Janice Patyk(74) *Attorney, Agent, or Firm* — Sterne, Kessler,
 Goldstein & Fox P.L.L.C.(57) **CLAIM**

The ornamental design for a bottle, as shown and described.

DESCRIPTION

FIG. 1 is a top perspective view of a bottle showing the claimed design;

FIG. 2 is a bottom perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The dashed broken lines in the figures show portions of the

bottle that form no part of the claimed design.

The dot-dash broken lines in the figures show boundaries
 that form no part of the claimed design.**1 Claim, 7 Drawing Sheets**(56)
